UNITED STATES PATENT OFFICE.

EDWARD A. DARST, OF EUREKA, ILLINOIS.

WIND-STACKER.

SPECIFICATION forming part of Letters Patent No. 692,246, dated February 4, 1902.

Application filed March 11, 1901. Serial No. 50,748. (No model.)

To all whom it may concern:

Be it known that I, EDWARD A. DARST, a citizen of the United States, residing at Eureka, in the county of Woodford and State of Illinois, have invented certain new and useful Improvements in Wind-Stackers; and I do hereby declare that the following is a full, clear, and exact description of the invention, which will enable others skilled in the art to which it appertains to make and use the same.

This invention pertains to improvements in straw-stackers as applied to threshing machinery and belongs to that class known as "wind-stackers."

The object of my invention is to provide a wind-stacker that will build a stack of any reasonable size as perfectly as by the machine known as the "web-stacker."

The prevailing difficulty with wind-stackers is that the stacks formed are finished with too large a base and are not of sufficient height. The result of this is that in a few weeks after the stack is built the straw has been reduced to a flat pile that stock of all kinds can run over and spoil. The fault lies in the fact that in building the stack the hood on the end of the chute must be placed at such an angle in order to deliver properly that the straw is caused to shoot over the outer side edge of the stack upon the ground, thus increasing the base size of the stack and not its height. The trouble arises from an inability to sufficiently extend the chute to allow the delivery-hood to be turned down so as to throw the straw directly down upon the stack at whatever height it may be at work. A further trouble is that the blast through the chute is so strong that the hood must be kept well above the stack in order to prevent the blast making a hole and blowing the straw in all directions. If the wind is blowing at any time during the stacking, the straw will be blown away from the hood as it leaves it, thus obviating these difficulties by providing a greater telescoping length for the chute, as will be hereinafter described, and also by the use of a deflector against which the straw may be blown.

In the accompanying drawings, Figure 1 is a side elevation of a threshing-machine, showing my improved device mounted there-

on. Fig. 2 is a plan view of a revoluble table which supports the chute. Fig. 3 is a perspective view of a bracket at the top of a brace. Fig. 4 is a face view of the brace mentioned above. Fig. 5 is a perspective view of the lower end of said brace, showing connections therefor. Fig. 6 is a top view of a bifurcated pipe attached to the brace described. Fig. 7 is a sectional end view of a supporting-pipe and eyes secured thereto. Fig. 8 is a rear view of a telescoping chute and braced truss therefor. Fig. 9 is a face view of a deflector located in front of the chute. Fig. 10 is a perspective view of a portion of the telescoping chute above referred to.

In the drawings, A indicates a revoluble table mounted in a suitable manner upon one end of a threshing-machine. The usual way of mounting this table is to carry it in rollers *a a*, as shown in Fig. 2, and the means for turning it consists of a worm *b*, which meshes with the teeth thereof, said worm being driven by a shaft *c*, having a hand-wheel *d* or other good means. Usually the table is swung back and forth by a reversing-gear, which moves the chute in an arc of a circle, as will be understood. By this arrangement the table will support a great weight and may be turned in any direction. The chute *B* is adapted to rise and fall by means of an elbow, which slips over a similar portion secured to said table. The means for carrying the chute consists of a mast comprising two bars *E E*, pivoted at their lower ends to projecting supports *F*, mounted on the table *A* in the usual manner. A bracket *G* is secured between the rods and supports the chute, while the said rods *E* are bent around above said chute and ascend somewhat above it, the ends being bolted together, as shown in Fig. 8. A double truss is arranged on the apparatus thus constructed and consists of two rods *H H*, bolted at their lower ends to the rods *E*. Their upper ends are secured to two braces *I I*, attached to lugs *J* on the rods *E*. Rods *H* are also attached to the arms *H* at one end and to the arms *E* at the other, thus forming a complete truss, which serves to brace the said rods *E*, so that they will withstand a great strain. In Fig. 1 a wheel *K* is shown between the lugs *J*, which is connected by a sprocket-chain or other suitable means to a winding mechanism located

on the table A, by which to draw the said rods E down toward it on the pivots at e in order to elevate the chute, as will be understood. I have not made an attempt to show 5 the said winding arrangement fully nor describe it at any length, since it is common to all of the machines of this character.

A pipe L is attached at one end to the rods E in any good manner and extends at right 10 angles therefrom for some distance and forms a support for the chute B as well as a track for the telescoping portion B' thereof. At about the middle of its length the pipe is provided with an upright brace M, which straddles 15 said pipe, as shown in Fig. 4. The upper end of the brace carries a tie N, one end of which carries the end of a rod O. The opposite end of the latter is carried in the top of the upper extension of the rods E. Near 20 the outer end of the pipe or track L is a lug P, to which one end of the rod Q is attached, the opposite end thereof being held by the said tie N. A rod R is attached to the upper end of the rods E, and its lower end is connected 25 to the brace M by means of a saddle M', to which said rod is attached, and the same bolt that secures the said brace M to the pipe L secures said saddle in place. Attached also to the rods E in a suitable manner is a pipe 30 or rod S, parallel with L, and whose opposite end is bifurcated, as shown in Fig. 6, and connected to the lower end of the brace M beneath the pipe L. Though not shown in Fig. 4, said rod S lies between a wheel T and the 35 extremities of M, the said wheel being provided for carrying the chain T' or like flexible means, which also runs over a wheel U, journaled in the region of the rods E. Owing to the enforced reduced scale of Fig. 1, I have 40 indicated the chain T' by dotted lines in order to more readily distinguish it from the other lines, but have shown a portion of it in Fig. 10. The chain is used to telescope the chute portion B' upon B. As shown in Fig. 1, the said 45 portion B' passes over B and its end carries a ring B'', to which the chain is attached. The outer end of the portion B' is supported on the pipe L by a roller V on a bail W, secured to the chute in any desired manner or as 50 shown in Fig. 10. Now by turning the wheel U by a crank or other means the portion B' will be telescoped upon B, and any desired extension within the limit of the device may be had. It will be noted that the truss composed 55 of the rods L, M, Q, O, and R make a substantial support for the chute no matter what length is used, and said chute by the means described may be swung in any direction or raised or lowered as desired.

60 The extreme end of the pipe or rod L pivotally supports a deflecting-plate 1 by means of a framework 2, to which said plate is secured. The upper end of the said frame has a cross-arm 3, upon which a T-fitting 4 is carried in a loose manner. The said pipe L is screwed into said fitting, and the said plate is thus permitted to swing at the will of the op-

erator. At two opposite sides of the pipe L is an eye 5, and at 6 and 7 are eyes to each of which the end of a wire is attached, as indicated at 8 and 9. Said wires run to the rear of the machine and take a turn around and are attached to wheels 10 and 11. When it is desired to swing the plate on its pivotal support, the crank 12 is turned in a direction to 75 swing the plate into the desired position, as will be understood.

In building a stack the chute is automatically oscillated in the arc of a circle, as previously mentioned. As the stack increases 80 in height the chute must be raised by swinging the truss E H H' I J on its pivots e, as before described. The hood is also given a direct downward inclination, so as to land the straw directly upon the top of the stack, said 85 hood being usually operated by means of cables from the operator's end of the thresher. However, since I provide the deflector 1 the exact position of the mouth of the hood is not important, since the straw is stopped at 90 the edge of the stack and must remain on top. As the chute swings the deflector swings around the outer edge of the stack and receives the straw. By means of the wires 8 and 9 the said deflector may be easily 95 manipulated and the stack shaped as desired. The increasing height of the stack necessitates the deflector being drawn closer to the chute, so as to gradually taper the stack toward the top, all of which will be readily understood.

As stated in the objects of my invention, my stacker will build a stack better than the web-stack. It must be understood that when using the latter machine several men are necessary upon the stack, while with the wind-stack as I construct it no men are necessary to shape the stack as the straw is delivered upon it. The telescoping portion B' of the chute ordinarily can only be drawn out 105 a short distance and hangs and is supported by the portion B. The usual distance the one overlaps the other is about three feet; but with my supporting-track the portions need overlap but two or three inches, or just 110 enough to prevent separation, and I am thereby able to gain a greater extension than ordinarily.

The deflector besides answering the purposes already described also serves as a guide 120 for the operator, who can determine by its position the outer edge of the stack and can thus manipulate it to shape the stack as desired and can also tell how his chute and its hood should be placed to best form the top. 125

Having thus described my invention, I claim—

1. In a stacker of the character described, a chute mounted to swing in any plane, an extension therefor adapted to be telescoped 130 upon said chute, a single track supported above the chute, a supporting-bail at the free end of the chute extension supported by said track and adapted to move along the same,

a deflecting-plate pivoted at the outer end of the track beyond the chute extension, said plate projecting above and below its pivotal point, flexible means attached to the plate, 5 one above and one below said point, means for operating the said flexible portions to move the plate on its pivot and means for shifting the telescoping portion of the chute substantially as set forth.

2. In a stacker of the character described, the combination of an extensible chute B' arranged to swing in all directions, a support for suspending such chute consisting of a frame or mast pivoted to the support which 15 carries the said chute at its rear end, a truss attached to the top of the said mast and extending forward to support the chute at its forward end, a track supported by said truss, 20 a bail W on the forward extremity of the extensible chute portion, the same being supported by the track and adapted to shift thereon, a deflecting-plate pivoted to the forward end of the track as shown, and the wires 8 and 9 attached to the deflector, one above 25 and one below its pivotal point, such wires being carried rearwardly and means for altering the length of the wires for shifting said deflector on its support as set forth.

3. In a stacker of the character described, 30 the chute B, the extension B' thereof, the latter adapted to slide on the former, a mast at the rear end of the chute, a truss connected thereto consisting of the rods O, Q, R, the post M, and the track L arranged as shown 35 and described, the latter attached to the mast, a bail on the forward end of the chute portion B' the same adapted to slide upon the said track, a support for the telescoping ends of the chute portions which consists of the 40 wheels T, U, one on the post M and the other on the mast, and a chain adapted to run upon the said wheels and having the telescoping end of the chute portion B' attached thereto for altering the length of the chute as the 45 chain is shifted as set forth.

4. In a stacker of the character described, the combination of the chute portions B and B', the mast at the rear end of said portion B, the truss O, Q, R, M and the track L arranged as shown and described, the deflecting-plate 1 pivoted to the forward end of the track, 50 the wires 8 and 9 attached thereto for shifting it, the bail W and wheel V for carrying the forward end of the chute portion B' on

the said track L, the chain T' connected to 55 the rear telescoping end of the said portion B', wheels T and U for the chain, the said chain adapted to both support and shift the said chute and means for elevating and lowering the entire mechanism for the purposes 60 set forth.

5. In a stacker the combination of the chute portions B and B', the mast composed of the arms E E carrying the chute, a truss secured to such mast and consisting of the arms H 65 and H', the arms J and I, the pulley K between the arms J, by which the mast is swung on its pivot to raise the chute, means for swinging said mast, the truss O, Q, M, R secured to the said mast for supporting the forward end of the chute, the track L connected with the said truss and mast and forming part of such truss, a bail W carrying the chute portion B' and adapted to shift on the said track L, a chain attached to the said 70 chute B' for supporting and shifting the same, wheels T, U for said chain, means for moving the chain to telescope the chute, the deflector 1 pivoted to the forward end of the track L for receiving the straw against it 75 from the chute, and the wires 8 and 9 for adjusting such deflector for the purposes specified.

6. In a wind-stacker, the combination of a straw-chute consisting of the stationary section B and sliding portion B' mounted on a thresher and adapted to swing thereon in all directions, a track L supported from the swinging support of said chute, a trussed support for said track consisting of the portions Q, M, 85 O and R and the bars E to which O and R are attached, a sliding bail for said portion B' and adapted to shift upon the said track whereby said portion B' may be telescoped 90 upon the portion B, means for telescoping said portions, a deflecting-plate 1 pivotally attached to the free end of the track and flexible portions 8 and 9 for moving same on its pivot, the same being within reach of the operator for the purposes described and all being 95 arranged substantially as set forth.

In testimony whereof I affix my signature in presence of two witnesses.

EDWARD A. DARST.
